MINIATURE CANDY BASKET

Louis Kutik, West Hollywood, Fla.

Application January 11, 1957, Serial No. 44,479

Term of patent 3½ years

(Cl. D58—4)

Fig. 1.

Fig. 2.

Fig. 3.

Fig. 4.

Fig. 1 is a perspective view of a miniature candy basket embodying my new design;

Fig. 2 is a perspective view thereof, showing the cover removed from the basket;

Fig. 3 is a top plan view thereof; and

Fig. 4 is an enlarged fragmentary horizontal sectional view thereof, taken on line 4-4 of Fig. 2.

I claim:

The ornamental design for a miniature candy basket, as shown.
